(57) **CLAIM**

The ornamental design for a shoe with detachable panels as shown and described.

DESCRIPTION

FIG. 1 is a top plan view of a shoe with detachable panels showing my new design;

FIG. 2 is a left-side elevational view thereof;

FIG. 3 is a right-side elevational view thereof;

FIG. 4 is a top plan view of the detachable panels shown in FIG. 1 decoupled from the shoe and in a flat configuration; and,

FIG. 5 is a perspective view of the detachable panels shown in FIG. 1 decoupled from the shoe.

The broken lines depict portions of the shoe with detachable panels that form no part of the claimed design. The dash-dot-dash broken lines illustrate boundaries that form no part of the claimed design.
